UNITED STATES PATENT OFFICE.

GEORGE H. BABCOCK, OF PLAINFIELD, NEW JERSEY.

DESIGN FOR A ROOFING-TILE.

SPECIFICATION forming part of Design No. 19,889, dated June 10, 1890.

Application filed May 14, 1890. Serial No. 351,815. Term of patent 14 years.

To all whom it may concern:

Be it known that I, GEORGE H. BABCOCK, a citizen of the United States, residing at Plainfield, in the county of Union and State 5 of New Jersey, have invented and produced a new and original Design for Roofing or Sheathing Tiles, of which the following is a specification, reference being had to the accompanying drawings, forming a part thereof.

10 My design relates to the architectural ornamentation of clay or other roof-tile by raised figures on the surface thereof.

Figure 1 is a face view of a tile embodying my design; and Fig. 2, a cross-section of Fig. 1, taken on the line *x* *x*, showing the relief of the pattern.

My design consists of a pattern resembling the form of a sea urchin, both in radiating character and in raised contour, the center 15 thereof rising prominently above the plane surface A of the tile.

This design is appropriate to various forms of tiles, but especially so to the form of interlocking tile herein shown, having a Gothic outline *a a* upon its lower portion.

25

The sea-urchin pattern B is raised from a depressed ground or circular channel *b*, and the rays or ridges *c* of the pattern radiate from the apex *d* obliquely (in cross-section) toward the said channel *b*, as seen in Fig. 2. 30

What I claim is—

The design herein shown and described for ornamenting the surface of a roof-tile, consisting in a sea-urchin pattern in high relief radiating from an apex central to the exposed face of the tile.

35
GEO. H. BABCOCK.
